FREQUENCY CHANGING SYSTEM

John A. Rado, Flushing, N. Y., assignor to Hazeltine Corporation, a corporation of Delaware

Application December 30, 1939, Serial No. 311,901

6 Claims. (Cl. 250—20)

This invention relates to frequency-changing systems and particularly to automatic frequency control for such systems embodied in modulated-carrier signal receivers of the superheterodyne type, especially television receivers.

Superheterodyne receivers provided with a frequency-changing system for selecting predetermined modulated-carrier signals and deriving therefrom intermediate-frequency modulated signals are well known. Such frequency-changing systems often are provided with automatic frequency control means including a correction circuit coupled to the oscillator circuit of the frequency-changing means for varying the effective reactance thereof to maintain the frequency of the oscillator circuit at the proper value necessary for deriving the selected intermediate-frequency signals. One system of controlling the oscillator frequency involves a control tube, the anode circuit of which is in parallel with the oscillator-tuned circuit and the control electrode of which is excited by a potential which has, by means of a suitable phasing network, been shifted 90 degrees with respect to the voltage across the tuned circuit of the oscillator so that the component of current which is common to the control-tube anode and the tuned circuit is 90 degrees out of phase with the voltage across this tuned circuit. The control tube thus simulates a reactance in parallel with the oscillator-tuned circuit. The magnitude of this reactance and hence the oscillator frequency, is determined by the mutual conductance of the control tube, which, in turn, is controlled by the bias voltage developed and fed to the control-tube grid return by a frequency discriminator or detector. In this way, the local oscillator frequency is shifted in a direction that tends to reduce the difference between the intermediate frequency developed and the mean frequency to which the intermediate-frequency selector circuits are tuned.

While the operation of such automatic frequency control systems is satisfactory for the conventional reception of modulated-carrier signals in the broadcast band of frequencies, it is often unsatisfactory for the reception of modulated-carrier signals of ultra-high frequencies, for example, in the frequency range assigned to television, because electron transit time effects are sufficient to affect the operation of both the oscillator and control tube, which effects interfere with the normal operation of the system when the receiver is tuned from one ultra-high frequency to another. Such transit time effects

cause the reactive current flowing in the control-tube anode circuit incidentally to depart from the desired 90-degree phase with respect to the oscillator voltage as the oscillator-tuned circuit is tuned to different frequencies in the ultra-high-frequency range.

It is an object of the present invention, therefore, to provide an improved frequency-changing system for a modulated-carrier signal receiver of the superheterodyne type which overcomes the above-mentioned difficulties and disadvantages of such arrangements of the prior art.

It is a more specific object of the invention to provide an improved automatic frequency control system for television signal receivers of the superheterodyne type.

In accordance with this invention, there is provided in an ultra-high-frequency modulated-carrier signal receiver a frequency-changing system for deriving from selected received modulated-carrier signals intermediate-frequency modulated-carrier signals, which comprises an oscillator circuit, means for selectively proportioning the constants of the oscillator circuit to oscillate at any desired one of a plurality of different frequencies, and a frequency-correction circuit coupled to the oscillator circuit including electron-discharge variable impedance means to adjust the frequency of the oscillator circuit to the proper value necessary for deriving the selected intermediate-frequency signals. In a frequency-changing system of this kind, the phase angle of the variable impedance means controlling the oscillator frequency incidentally tends to vary with respect to the oscillator circuit voltage with variations in frequency due to variations in the effect of electron transit time of the impedance means, thereby to impair the frequency correction of the oscillator. To counteract any tendency of the phase angle of such variable impedance means to vary with variations in frequency resulting from the selection of any desired one of the plurality of different oscillator frequencies, an oscillator voltage compensating circuit is coupled to the frequency-correction circuit and means are provided for selectively proportioning the constants of the compensating circuit to counteract any tendency of the phase angle of such variable impedance means to vary with variations in frequency. The invention also comprises unicontrol means for simultaneously operating the means for selecting the constants of the oscillating and compensating circuits, whereby any tendency in the frequency-correction circuit toward undesired phase angle varia-

tion resulting from the selection of a desired oscillator frequency is minimized. In a preferred embodiment of the invention the correction circuit includes a vacuum tube connected to simulate a variable impedance and the desired 90-degree phase relation between the current of this vacuum tube and the oscillator voltage is maintained by a voltage selector which controls the electron transit time and the transadmittance angle in both the oscillator and the control tube.

For a better understanding of the present invention, together with other and further objects thereof, reference is had to the following description taken in connection with the accompanying drawing, and its scope will be pointed out in the appended claims.

In the accompanying drawing the single figure is a circuit diagram, partly schematic, of a complete superheterodyne receiver embodying the present invention.

Referring now more particularly to the drawing, there is shown schematically a receiver of the superheterodyne type including an antenna system 10, 10 connected to a radio-frequency amplifier 11, to which is connected in cascade, in the order named, a frequency-changing system including a modulator 12 to which is coupled by condenser 46 a local oscillator 24, an intermediate-frequency amplifier 13, and a video-signal channel comprising a video-intermediate-frequency amplifier 14, a detector 15, a video-frequency amplifier 16, and an image-reproducing device 17. Also coupled in cascade with the intermediate-frequency amplifier 13 is a sound-signal channel comprising, in the order named, a sound-intermediate-frequency amplifier 18, a detector 19, an audio-frequency amplifier 20, and a sound-reproducing device 21. The elements or components 10-21, inclusive, all may be of conventional well-known construction so that a detailed illustration and description thereof is deemed unnecessary herein. A frequency discriminator 19a, of any suitable or conventional type, is coupled to the sound intermediate-frequency amplifier 18 and its bias output applied to the oscillator 24 over a conductor 19b, as described in detail hereinafter.

Neglecting for the moment the particular operation of the frequency-changing system embodying the present invention, the system above-described includes the features of a conventional superheterodyne television receiver. The operation of such a receiver being well understood in the art, detailed explanation thereof is deemed unnecessary. In brief, however, the tunable circuits of the radio-frequency amplifier 11 and frequency changer 12-24, are adjusted to select the desired modulated-carrier signals intercepted by the antenna system 10, 10 and to convert them to intermediate-frequency signals. These signals are selected and amplified by the intermediate-frequency amplifier 13 and translated therefrom to the video intermediate-frequency amplifier 14 and to the sound-intermediate-frequency amplifier 18. In the video-signal channel of the receiver the video-intermediate-frequency signals are translated to the detector 15 wherein the video-frequency modulation components are derived. These video-frequency components are amplified in the video-frequency amplifier 16 and reproduced by the image-reproducing device 17 in a conventional manner. The sound-frequency modulation components are derived by the detector 19 and amplified by the audio-frequency amplifier 20, the amplified audio-frequency sig-

nals being reproduced by the loudspeaker 21 in a conventional manner.

Referring now more particularly to the parts of the frequency-changing system comprising the present invention, the oscillator system 24 comprises an oscillator tube 23 and a control tube 22, both of the pentode type. The oscillator, per se, is a conventional Colpitts oscillator, a type at present commonly used in television receivers. The oscillator is provided with means for selectively proportioning the constants of the oscillator circuit to oscillate at any desired one of a plurality of different frequencies comprising a frequency-determining circuit comprising including a selector switch 25 for selectively including one of a plurality of fixed inductances 26, 27, 28 in the circuit, each being tuned by inherent circuit capacitance indicated conventionally by dotted-line condenser 29. The capacitance 29 comprises the inherent capacitance of the inductance element in circuit, wiring capacitance, and tube inter-electrode capacitances. In order to develop an oscillator circuit voltage, one terminal of such frequency-determining circuit is connected directly to the screen of the oscillator tube 23, acting as an anode, and to the cathode through a coupling condenser 30. The grid of the oscillator tube 23 is connected to the other terminal of the frequency-determining circuit through a grid leak 31 and condenser 32 and a by-pass condenser 33. The suppressor grid of the tube 23 is grounded, while the cathode is grounded for direct current through a radio-frequency choke 35. Condenser 30, in conjunction with the inherent cathode-to-ground capacitance 30a of tube 23, form the capacitance divider required by the Colpitts circuit.

The frequency-changing system is provided with a frequency-correction circuit coupled to the oscillator circuit including electron-discharge variable impedance means, comprising the control tube 22, connected to simulate a variable impedance to adjust the frequency of the oscillator circuit to the proper value for deriving the selected intermediate-frequency signals. Specifically, the plate of the tube 23 is connected by a blocking condenser 36 to the control grid of the control tube 22, the anode circuit of this tube being connected directly across the frequency-determining circuit, as indicated. The plate of the tube 23 is used here merely as a coupling device. The cathode circuit of the control tube 22 includes undesired but inherent cathode lead inductance 37 and a conventional biasing circuit 38. As will be explained hereinafter in greater detail, the phase angles of the impedance means comprising tube 22 and of the oscillator vacuum tube 23 incidentally tend to vary with respect to the oscillator circuit voltage with variations in frequency due to variations in the effect of electron transit time of the vacuum tubes, thereby to impair the frequency correction of the oscillator. To avoid such variations of the phase angles of these tubes with frequency, the frequency-changing system includes an oscillator voltage compensating circuit comprising a plurality of compensating resistors 39, 40 and 41. This compensating circuit is coupled to the frequency-correction circuit, specifically, space current is supplied from a source, indicated at +B, to the anodes and screens of tubes 22 and 23 through one of the resistors 39, 40 and 41. The frequency-changing system additionally includes means for selectively proportioning the constants of the compensating circuit to counteract any tendency of the phase angles of the impedance means and of the oscillator vac-

uum tube to vary with frequency resulting from the selection of any desired one of the plurality of different oscillator frequencies, this means comprising a selector switch 42 which is arranged selectively to connect the anode circuits of tubes 22 and 23 through one of the resistors 39, 40 and 41 to the space current source +B. The plate circuit of the tube 23 includes a resistor 43 which, with the inherent input capacitance of the control tube 22 and output capacitance of tube 23, represented by the dotted-line condenser 44 and hereinafter referred to as input capacitance of tube 22, comprises a phase-shifting impedance for applying to the control grid of tube 22 a voltage somewhat less than 90 degrees displaced in phase from that across the frequency-determining circuit of the oscillator. The automatic frequency control bias voltage from the frequency discriminator 19a is applied by conductor 19b to the control grid of the control tube 22 to determine its transconductance. The selector switches 25 and 42 are connected for simultaneous operation by a unicontrol mechanism, conventionally shown by the dashed line 45.

The value of resistor 43 is so chosen in relation to the values of effective tube transadmittances and the input capacitance 44 of tube 22 that the output current of tube 22 is 90 degrees out of phase with the oscillator voltage at a given frequency. At the oscillator frequencies required in receiving television signals there is an appreciable transadmittance angle between the voltage applied to the control electrode of tube 22 and the current output thereof and between the voltage developed at the screen of tube 23 and the anode current thereof which is a function of frequency and of the operating voltages. The values of the resistors 39, 40, and 41 are, therefore, chosen to so alter the operating voltages of tubes 22 and 23 as to maintain the resultant phase angle between the oscillator voltage and reactive current output of tube 22 at 90 degrees for each selected oscillator frequency.

In considering the operation of the frequency-changing system involving the present invention, it will be assumed that a predetermined modulated-carrier signal is selected and that the switch 25 is operated to connect the proper one of the fixed inductance elements 26, 27, or 28 into the oscillator circuit to produce the desired local oscillations, the local oscillator operating in a conventional manner by virtue of the coupling between its anode (screen) and its cathode through the frequency-determining circuit. These oscillations are applied to the modulator 12 through the condenser 46. This causes the modulator 12 to produce the desired intermediate-frequency modulated-carrier signal. Any slight variation of the intermediate frequency supplied to the frequency discriminator 19a, due to drifting or mistuning of the oscillator, causes the discriminator 19a to develop a corrective control-bias voltage which is applied to the control electrode of control tube 22 over conductor 19b to vary the transconductance of tube 22. Since the anode circuit of the control tube 22 is in parallel with the frequency-determining circuit of the oscillator tube 23 and its anode current, which is effectively a control current supplied to the frequency-determining circuit, is 90 degrees out of phase with the voltage across the oscillator circuit, the control tube simulates a variable reactance across the frequency-determining circuit. As a result, a change of transconductance of the tube 22 produced by the automatic frequency con-

trol-bias voltage changes the frequency of the oscillator to maintain the intermediate frequency at its desired mean value. However, as stated above, in changing from one oscillator frequency to another by means of switch 25, there is an incidental tendency accompanying these shifts in frequency for the current in the correction circuit to vary in phase with respect to the oscillator circuit voltage.

10 The factors determining the magnitude of the phase angle of the current output of tube 22 with respect to oscillator voltage are:

15 1. The phase angle at the oscillator frequency of the impedance of resistor 43 and input capacitance 44 in parallel.

2. The phase angle of the cathode-to-ground impedance of control tube 22.

3. The transadmittance angles from control electrode to anode of control tube 22 and from screen to anode of oscillator tube 23.

20 The above three quantities are affected in magnitude by variation of oscillator frequency; in addition, the magnitude of the two transadmittance angles may be varied over a considerable range by varying the unidirectional potentials applied to anode and screen.

25 In accordance with this invention, the unidirectional voltages applied to the anodes and screens of the tubes 23 and 22 are controlled by means of the selector switch 42 to compensate for the tendency of the other factors to change the phase angle of the control-tube current with variation of the selected oscillator frequency.

30 A specific example will illustrate the operation to be expected in the system of this invention. Let it be assumed, for example, that selector switch 25 connects the tuning inductance 26 into the frequency-determining circuit of the oscillator and that the voltage from source +B

35 is applied to the anodes and screens of tubes 22 and 23 through resistor 39 by switch 42 and that oscillation commences at the desired frequency. Neglecting for the moment electron transit time effects in the vacuum tubes 22 and 23 and all

40 circuit impedances except capacitance 44, a current in phase with the oscillator voltage flows in capacitance 44 and a voltage appears at the control electrode of tube 22 which lags the oscillator voltage by 90 degrees. The resulting anode cur-

45 rent of tube 22 is at the proper 90-degree phase angle with respect to the oscillator voltage. However, if electron transit time in tube 23 be considered, it causes the plate current of tube 23

50 to lag somewhat behind the oscillator voltage and likewise, for the same reason, the anode current in control tube 22 lags behind its control electrode voltage. Furthermore, cathode-to-ground impedance of tube 22, particularly lead inductance 37, increases this lag. The necessary correction

55 for this set of conditions can be made by cancelling some of the effect of the reactance of ca-

60 pacitance 44 by means of resistor 43 in the anode circuit of tube 23.

65 But now should switch 25 be operated to select another tuning inductance, for example, inductance 27, to develop another oscillator frequency which is higher than the oscillator frequency produced by the tuning inductance 26, the electron transit time, while of the same absolute value, is now a larger fraction of the period of the generated wave so that the phase shift of the output current of oscillator tube 23 and of the anode current of the control tube 22 with respect to the oscillator voltage is increased. At the same time,

70 75 resistor 43 is now of too high a value to cancel

the required portion of the phase shift due to capacitance 44, which is lower in reactance at the higher frequency. However, in accordance with the present invention, both these variations in phase angle are compensated for by the simultaneous selection by means of simultaneous operation of the switch 42 with the switch 25, of another operating voltage of sufficiently higher value to shorten the electron transit times in both vacuum tubes and thereby to reduce the trans-admittance angles therein, thus restoring the proper 90-degree phase between the anode current of tube 22 and the oscillator voltage.

The fixed-inductance elements 26, 27, and 28 are selectively proportioned to cause the oscillator circuit to oscillate at any desired one of three different frequencies. The fixed compensating resistors 39, 40, and 41 likewise are selectively proportioned so that the voltage applied by the compensating circuit to control the electron transit times of the vacuum tubes 22 and 23 counteracts any tendency of the control current supplied to the oscillator-tuned circuit by the vacuum tube 22 in the correction circuit to vary in phase with respect to the oscillator circuit voltage by virtue of variations in frequency resulting from the selection of any desired one of the three different oscillator frequencies. Thus, the unicontrol means 45 operates the switches 25 and 42 simultaneously to select the constants of the oscillating and compensating circuits so that any tendency toward variation in phase of the control current resulting from the selection of a desired oscillator frequency is minimized.

The following values have been found satisfactory in the design of a frequency-changing system according to the present invention:

Video-intermediate frequency	megacycles	12.75
Sound-intermediate frequency	do	8.25
Radio-frequency band range (1)	do	44-50
Radio-frequency band range (2)	do	50-56
Radio-frequency band range (3)	do	66-72
Oscillator frequency (1)	do	58
Oscillator frequency (2)	do	64
Oscillator frequency (3)	do	80
Inductance 26	microhenries	0.20
Inductance 27	do	0.15
Inductance 28	do	0.10
Inductance 37	do	2.00
Resistor 39	ohms	5,000
Resistor 40	do	2,500
Resistor 41	do	1,000
Resistor 43	do	150-200
Capacitance 29	micro-microfarads	30
Capacitance 44	do	20
Control tube 22		6AC7
Oscillator tube 23		6AC7
Voltage source +B	volts	250-300
A. F. C. Control-bias voltage range	volts	2-6
Phase shift due to electron transit time at 50 megacycles	degrees	35-40

While there has been described what is at present considered to be the preferred embodiment of this invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. In an ultra-high-frequency modulated-

carrier signal receiver, a frequency-changing system for deriving from selected received modulated-carrier signals intermediate-frequency modulated-carrier signals comprising, an oscillator circuit, means for selectively proportioning the constants of said oscillator circuit to oscillate at any desired one of a plurality of different frequencies, a frequency-correction circuit coupled to said oscillator circuit including electron-discharge variable impedance means to adjust the frequency of said oscillator circuit to the proper value for deriving the selected intermediate-frequency signals, the phase angle of said impedance incidentally tending to vary with respect to the oscillator circuit voltage with variations in frequency due to variations in the effect of electron transit time of said impedance means thereby to impair the frequency correction of said oscillator, an oscillator voltage compensating circuit coupled to said correction circuit, and means for selectively proportioning the constants of said compensating circuit to counteract any tendency of the phase angle of said impedance to vary with frequency resulting from the selection of any desired one of said plurality of different frequencies.

2. In an ultra-high-frequency modulated-carrier signal receiver, a frequency-changing system for deriving from selected received modulated-carrier signals intermediate-frequency modulated-carrier signals comprising, an oscillator circuit, means for selectively proportioning the constants of said oscillator circuit to oscillate at any desired one of a plurality of different frequencies, a frequency-correction circuit coupled to said oscillator circuit including electron-discharge variable impedance means to adjust the frequency of said oscillator circuit to the proper value for deriving the selected intermediate-frequency signals, the phase angle of said impedance incidentally tending to vary with frequency due to variations in the effect of electron transit time of said impedance means thereby to impair the frequency correction of said oscillator, a compensating circuit coupled to said correction circuit, means for selectively proportioning the constants of said compensating circuit to counteract any tendency of the phase angle of said impedance to vary with frequency resulting from the selection of any desired one of said plurality of different frequencies, and unicontrol means for simultaneously operating the means for selectively proportioning the constants of said oscillating and compensating circuits, whereby said tendency of the phase angle of said impedance to vary with frequency resulting from the selection of the desired oscillator frequency is minimized.

3. In an ultra-high-frequency modulated-carrier signal receiver, a frequency-changing system for deriving from selected received modulated-carrier signals intermediate-frequency modulated-carrier signals comprising an oscillator circuit, means for selectively proportioning the constants of said oscillator circuit to oscillate at any desired one of a plurality of different frequencies, a frequency-correction circuit including a vacuum tube connected to simulate a variable impedance coupled to said oscillator circuit to adjust the frequency of said oscillator circuit to the proper value for deriving the selected intermediate-frequency signals, the phase angle of said impedance incidentally tending to vary with respect to the oscillator circuit voltage with variations in frequency due to electron

transit time effects in said vacuum tube, a compensating circuit coupled to said correction circuit, and means for selectively proportioning the constants of said compensating circuit to counteract any tendency of the phase angle of said impedance to vary with frequency resulting from the selection of any desired one of said plurality of different frequencies.

4. In an ultra-high-frequency modulated-carrier signal receiver, a frequency-changing system for deriving from selected received modulated-carrier signals intermediate-frequency modulated-carrier signals comprising, an oscillator circuit including a vacuum tube, means for selectively proportioning the constants of said oscillator circuit to oscillate at any desired one of a plurality of different frequencies, a frequency-correction circuit including a vacuum tube connected to simulate a variable impedance coupled to said oscillator circuit to adjust the frequency of said oscillator circuit to the proper value necessary for deriving the selected intermediate-frequency signals, the phase angles of trans-admittance of said vacuum tubes incidentally tending to vary with variations in frequency due to electron transit time effects in said vacuum tubes, a compensating circuit coupled to said correction circuit, and means for selectively proportioning the constants of said compensating circuit to counteract any tendency of said phase angles of transadmittance to vary with variations in frequency resulting from the selection of any desired one of said plurality of different frequencies.

5. In an ultra-high-frequency modulated-carrier signal receiver, a frequency-changing system for deriving from selected received modulated-carrier signals intermediate-frequency modulated-carrier signals comprising, an oscillator circuit, means for selectively proportioning the constants of said oscillator circuit to oscillate at any desired one of a plurality of different frequencies, a frequency-correction circuit including a vacuum tube coupled to said oscillator circuit for supplying control current thereto to adjust the frequency of said oscillator circuit to the

proper value for deriving the selected intermediate-frequency signals, said control current incidentally tending to vary in phase with respect to the oscillator circuit voltage with variations in frequency due to electron transit time effects in said vacuum tube, and a compensating circuit coupled to said vacuum tube for controlling its electron transit time effects and having constants selectively proportioned to counteract any tendency of said control current to vary in phase with frequency resulting from the selection of any desired one of said plurality of different frequencies.

6. In an ultra-high-frequency modulated-carrier signal receiver, a frequency-changing system for deriving from selected received modulated-carrier signals intermediate-frequency modulated-carrier signals comprising, an oscillator circuit including a vacuum tube having an anode circuit for developing an oscillator circuit voltage, means for selectively proportioning the constants of said oscillator circuit to oscillate at any one of a plurality of different frequencies, a frequency-correction circuit coupled to said oscillator circuit including a vacuum tube having an anode circuit which carries a current that is desirably 90 degrees out of phase with respect to said oscillator circuit voltage whereby said last-named anode circuit simulates a variable reactance to adjust the frequency of said oscillator circuit to the proper value for deriving the selected intermediate-frequency signals, the current in the anode circuit of said frequency-correction tube incidentally tending to vary from said desired 90-degree phase relation with respect to the oscillator circuit voltage with variations in frequency due to electron transit time effects in both of said tubes, a compensating circuit coupled to said anode circuits, and means for selectively proportioning the constants of said compensating circuits to counteract any tendency of said anode circuit currents to vary in phase with frequency resulting from the selection of any desired one of said plurality of different frequencies.
